United States Patent Office.

ROBERT T. BURNETT, OF NEW YORK, N. Y.

Letters Patent No. 85,998, dated January 19, 1869.

IMPROVEMENT IN MEAT-SMOKING APPARATUS.

The Schedule referred to in these Letters Patent and making part of the same.

To all whom it may concern:

Be it known that I, ROBERT T. BURNETT, of New York, in the county of New York, and State of New York, have invented a new and improved Meat-Smoking Apparatus; and I do hereby declare that the following is a full, clear, and exact description thereof, which will enable others skilled in the art to make and use the same, reference being had to the accompanying drawings, forming part of this specification, in which—

Figure 1 is a vertical section of my improved apparatus.

Figure 2 is a detail front view of the furnace.

Similar letters of reference indicate corresponding parts.

My invention has for its object to furnish a simple, convenient, and effective apparatus for smoking meat, fish, and other similar articles, by means of which the smoking may be done easily and thoroughly, and without danger of burning the articles being smoked; and

It consists in the construction and combination of the various parts of the apparatus, as hereinafter more fully described.

A is the body of the apparatus, which I prefer to make of sheet-iron, and cylindrical in form, and which may be made of any desired diameter, according to the amount of work required to be done.

B is the bottom of the cylinder, which is made of wood, and has a hole in its middle part to receive the end of the smoke-pipe C.

The cylinder A B is supported upon legs D, of such a length as to raise the body of the apparatus to such a height as to leave space beneath it to receive the furnace E and pipe C.

The ends or heads of the furnace E are made of cast-iron, and the body of said furnace of sheet-metal, to which the said cast-iron ends should be secured by rods.

The front end of the furnace E is provided with a door for the introduction of the fuel to make a smoke, and with a damper to regulate the draught.

The grate, or fire-plate e¹, I prefer to make in the form of a section of a cylinder, to furnish a large surface for the fuel to rest upon, and at the same time a large air-chamber for the air to support combustion.

The rear end of the furnace E is cast with a flue leading out of its upper part, extending downward, and receiving the end of the smoke-pipe C.

The ends of the furnace E are also cast with upwardly-projecting lugs e², by means of which the said furnace may be secured to and suspended from the bottom, B, of the apparatus.

The smoke-pipe C extends from the furnace E horizontally across the bottom of the apparatus, and then turns and passes back above and parallel with the first part of said pipe, to the centre of the apparatus, where it turns at right angles and passes in through the hole in the bottom, B, of the cylinder A.

The double bend of the pipe C, I prefer to make of cast-iron, as it saves the making of two elbows.

The hole through the bottom, B, through which the pipe C passes, is made larger than the pipe C, the space between said pipe and the sides of said hole being occupied with a circular perforated ring-plate E, which supports the said pipe C in place, and, at the same time, admits a limited amount of air, which has a tendency to keep the apparatus and its contents cool.

The pipe C is designed to be made as long as possible, to allow the smoke to part with the most of its heat before entering the cylinder A.

To the upper end of the cylinder A is attached a ring-plate, G, to the inner edge of which is attached a band, H, from which is suspended a ring, I, upon which are placed the movable hooks J, by means of which the articles to be smoked are suspended, so that the said hooks may be adjusted closer together or further apart, according as the size of the articles to be smoked may require.

Upon the upper edge of the band H is fitted a cover, K, which is made to fit smoke-tight, and is hinged at one edge, so that it may be readily turned back, for convenience in putting in and taking out the articles to be smoked.

In the middle of the cover K is placed a ventilator, L, which is so constructed that the escape of the smoke, and consequently the draught through the apparatus, may be regulated at pleasure.

Having thus described my invention,

I claim as new, and desire to secure by Letters Patent—

1. An improved smoking-apparatus, formed by the combination of the furnace E, constructed as described, pipe C, perforated ring-plate F, bottom, B, cylinder A, ring-plate G, band H, ring I, adjustable hooks J, cover K, and ventilator L, with each other, substantially as herein shown and described, and for the purpose set forth.

2. The band H and suspended ring I, for the adjustable hooks, in combination with the ring-plate G, and cover K of a smoking-apparatus, substantially as herein shown and described, and for the purpose set forth.

3. The combination of the perforated ring-plate F with the pipe C and bottom, B, of a smoking-apparatus substantially as herein shown and described.

4. Forming the ends of the furnace E with lugs, to enable the said furnace to be suspended from the bottom, B, of a smoking-apparatus, substantially as herein shown and described.

The above specification of my invention signed by me, this 9th day of December, 1868.

ROBT T. BURNETT.
